FOREIGN PATENT DOCUMENTS

CN 202430188574.0 * 8/2024

Primary Examiner — S. Bryan Reinholdt, Jr.*(74) Attorney, Agent, or Firm* — troutman pepper locke;
Tim Tingkang Xia, Esq.(57) **CLAIM**

The ornamental design for a cup lid as shown and described.

DESCRIPTION

FIG. 1 is a first perspective view of a cup lid according to my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a second perspective view thereof.

The broken lines depict portions of the cup lid that form no part of the claimed design.
